METHOD OF AND APPARATUS FOR PLATING

Robert N. Brown, Detroit, Mich., assignor to
 Packard Motor Car Company, Detroit, Mich.,
 a corporation of Michigan

Application August 7, 1933, Serial No. 683,968

5 Claims. (Cl. 204—5)

This invention relates to a process of and apparatus for plating articles.

It is sometimes desirable to plate articles so that the coating is of varying thicknesses. In order to obtain different thicknesses of coating, it has previously been necessary to subject the article to more than one plating operation. This has been necessary because the article must be adjusted in its carrier to place the portion having a desired thickness of coating in a relation where it will not again be submerged in the bath, or portions of the article must be covered with paraffin or similar material in order to prevent further coating thereof if complete submersion in the bath is resorted to. The multiple plating operations or multiple handling of an article during plating is expensive and requires time, and it is an object of this invention to provide apparatus for carrying an article during a single plating process so that different portions will have coatings of different thicknesses.

Another object of the invention is to provide apparatus for holding bolts submerged in a bath during a plating process so that the coating deposited on the head portion will be thicker than the coating deposited on the shank portion.

A further object of the invention is to provide an apparatus for holding articles during a plating process so that a portion of the article is shielded in a manner such that it will receive a thinner coating than the unshielded portion.

Still another object of the invention is to provide a novel and improved plating process wherein the coating deposited on a submerged article is thinner on one portion than on another portion.

Other objects of the invention will appear from the following description taken in connection with the drawing, which forms a part of this specification, and in which:

Fig. 1 is a sectional view of plating apparatus incorporating my invention;

Fig. 2 is a sectional view taken on line 2—2 of Fig. 1 with parts of the apparatus broken away.

Referring now to the drawing by characters of reference, 10 represents an open top tank for containing an electrolyte 11 which in this instance is a chromic acid solution H_2CrO_4 . Extending into the electrolyte is an anode 12 connected with an electric current by wiring 13 which is fixed thereto by a connector 14 held by a set screw 15. Forming a part of such wiring is 55 a manually operable switch 16. The wiring con-

nects with a source of electricity, such as a battery 17.

Extending across the tank and resting on the top edges thereof is a supporting member having a copper core 18 surrounded by a layer of insulating material 19. Wiring 20 leads from the battery and is connected with the end of the supporting bar core by a connector 21 fastened by a set screw 22. Suspended from the bar and extending into the electrolyte is a holder for an article to be plated, which in this instance is a bolt 23. The holder consists of a pair of partly insulated wire members 24 having the upper ends extending through an opening in the bar and fixed in contact with the core by a set screw 25. The wires are of a length to extend into the acid bath when the bar is resting on the tank and the lower end portions are bent to form resiliently contacting fingers providing an opening 26 therebetween through which the shank of a bolt can be readily axially inserted or removed. Current passes from the bar core through the holder to the bolt so that it forms the cathode.

When the above described apparatus is associated and the switch 16 is closed, then the electrolyte is decomposed by the electric current and chrome adheres to the bolt. This plating will be of substantially uniform thickness on the entire bolt surface unless some provision is made to lessen the deposit in certain areas.

In many instances, different thicknesses of plating on articles are necessary or desirable. A thick heavy plating on a bolt head is desirable because of repeated applications of a wrench thereto and, at the same time, a considerably thinner plating on the bolt shank is desirable if retapping of the threads is to be avoided. Two thicknesses of plating have heretofore required multiple plating operations or adjustment of the article support after being submerged in the bath.

In order to obtain two thicknesses of plating on different surfaces of an article without removal from the bath or adjustment of the apparatus or the article during the process, I provide means for limiting the electrolytic action in the bath adjacent the portions of the article to receive the thinner coating. In the present instance, a shield is provided around the shank of the bolt so that the electrolytic action will be less adjacent the shank than adjacent the head. The shield consists of a cylindrical casing 27 formed of insulation material having one end adjacent the wires 24 removable and formed with an opening 28 aligned with the opening 26 so 55

that the bolt shank can project therethrough. An arm 28 extends upwardly from this end of the cylinder, and one end of a hanger in the form of a wire 30, is fixed in the arm. The other end of the hanger is fixed to the supporting bar and an insulation sleeve 31 covers the portion of the hanger intermediate the arm and the bar.

5 Openings 32 are provided in the cylinder shield which with the opening 28 allow the electrolyte to fill the casing when submerged. The casing 27 acts as a shield around the bolt shank which reduces the chemical action produced by the electric current as compared with that in the surrounding bath. The degree to which such chemical 10 action causes deposition of chromium on the bolt shank is regulated by the size or number of openings, and thus the thickness of plating on the bolt shank relative to the thickness of the plating on the bolt head can be regulated as desired.

15 20 It will be seen that the apparatus herein described can be submerged in a plating bath and that portions of an article carried thereby will be coated different thicknesses without any further adjustment or repeated process operation.

25 30 Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. Process for chrome plating bolts, comprising 25 submerging a bolt as a cathode in a chrome acid solution, encasing the bolt shank in a member provided with means permitting limited electrolytic action around the bolt shank, suspending an anode in the zone of the bolt, and passing current through the solution by means of said 40 bolt and anode to form different thicknesses of plating on the shank and head of the bolt.

2. An electrolytic apparatus comprising a re-

ceptacle, an electrically conducting support adjacent the top of said receptacle, an article enclosing member of non-conducting material depending from said support, said article enclosing member having a horizontally extending chamber open at one end, and a pair of resilient fingers of conducting material electrically connected to said support and disposed adjacent the open end of said chamber.

3. An electrolytic apparatus comprising a receptacle, an electrically conducting support adjacent the top of said receptacle, an article enclosing member of non-conducting material depending from said support, said article enclosing member having a horizontally extending chamber open at one end, the walls of said chamber being perforated.

4. An electrolytic apparatus comprising a receptacle, an electrically conducting support adjacent the top of said receptacle, an article enclosing member of non-conducting material depending from said support, said article enclosing member having a horizontally extending chamber open at one end, and a pair of resilient fingers of conducting material electrically connected to said support and disposed adjacent the open end of said chamber, said fingers being adapted to grip an article therebetween and support said article partially within said chamber.

5. An electrolytic apparatus comprising a receptacle, an electrically conducting support adjacent the top of said receptacle, an article enclosing member of non-conducting material depending from said support, said article enclosing member having a horizontally extending chamber open at one end, a member having a central aperture and adapted to partially close said open end of said chamber, and article supporting means electrically connected to said support and disposed outside of said chamber and adjacent 40 said aperture.

ROBERT N. BROWN.
